US00D766211S

(12) **United States Design Patent** (10) **Patent No.:** **US D766,211 S**
Choi et al. (45) **Date of Patent:** **** Sep. 13, 2016**

(54) **SPEAKER**

- (71) Applicant: **Samsung Electronics Co., Ltd.**, Suwon-si, Gyeonggi-do (KR)
- (72) Inventors: **Su An Choi**, Seoul (KR); **Sungil Bang**, Seoul (KR); **Yonggu Do**, Cheonan-si (KR)
- (73) Assignee: **SAMSUNG ELECTRONICS CO., LTD.**, Suwon-Si, Gyeonggi-Do (KR)
- (**) Term: **15 Years**
- (21) Appl. No.: **29/530,806**
- (22) Filed: **Jun. 19, 2015**

(30) **Foreign Application Priority Data**

- Dec. 31, 2014 (KR) 30-2014-0064546
- (51) **LOC (10) Cl.** **14-03**
- (52) **U.S. Cl.** ..... **USPC** **D14/211; D14/216**
- (58) **Field of Classification Search**
USPC D14/211, 216, 209.1, 217, 496; D13/107, 108; D28/76; D9/504; 181/144-147, 153, 151, 155, 199; 381/350, 349, 338, 386; D19/101, 179; 401/6, 126
- CPC H05K 5/00; H04R 25/00; H04R 1/10; H04R 1/02; A47K 5/08
- See application file for complete search history.

Primary Examiner — Paula Greene*(74) Attorney, Agent, or Firm* — Ladas & Parry LLP(57) **CLAIM**

We claim the ornamental design for the speaker, as shown and described.

DESCRIPTION

FIG. 1 is the front perspective view of the speaker showing our new design;

FIG. 2 is the front view thereof;

FIG. 3 is the view thereof;

FIG. 4 is the left-side view thereof;

FIG. 5 is the right-side view thereof;

FIG. 6 is the top plan view thereof; and,

FIG. 7 is the bottom plan view thereof.

The broken lines depict portions of the speaker that form no part of the claimed design.

1 Claim, 7 Drawing Sheets# US D766,211 S
